UNITED STATES PATENT OFFICE.

JAMES H. HUNTER, OF NEW YORK, N. Y.

ELECTRIC DANGER-ALARM FOR RAILWAY BLOCK-SIGNALS.

SPECIFICATION forming part of Letters Patent No. 417,188, dated December 10, 1889.

Original application filed February 19, 1889, Serial No. 300,475. Divided and this application filed August 31, 1889. Serial No. 322,553. (No model.)

To all whom it may concern:

Be it known that I, JAMES H. HUNTER, a subject of the Queen of Great Britain, and a resident of the city, county, and State of New York, have invented certain Improvements in Electric Danger-Alarms for Railway Block-Signals, of which the following is a specification.

My invention relates to that class of danger-alarms for electric block-signal systems on railways wherein a signal is sounded or displayed in the cab of the locomotive whenever there is danger ahead—as, for example, when there is a train in the same block. These danger-alarm systems have employed suitable electrical conductors connecting the magnets of circuit breakers or relays at points which divide the road up into blocks or sections, and also at other points where needed. In operating such systems an electric-current generator, usually a dynamo run by a special engine, is mounted on the locomotive, said generator being in a normally-closed circuit on the locomotive.

In a pending application of mine, Serial No. 300,475, of which this application is a division, mechanical devices are shown whereby the normally-closed circuit on the locomotive is broken when the locomotive enters a block, and a partial circuit on the locomotive, including the generator, is connected with a track or line circuit or partial circuit controlled by a relay, whereby, if the said relay is set to "danger," the newly-formed circuit will be broken or incomplete and a danger-signal will be given to the engineer; but if the relay be set to "safety" the newly-formed circuit will be complete or closed and the engineer will receive no signal. It has been

found by experience that the electro-motive force generated by the means usually employed will not remain constant, and when a considerable external resistance is shunted into the circuit by the connecting of the partial circuit on the locomotive with a comparatively long line or track circuit the electro-magnet controlling or operating the danger-signal is rendered very unreliable. To obviate this defect is the purpose of my present invention, which consists in introducing into the circuit on the locomotive a device which

I call a "distributer," comprising a peculiar circuit breaker and closer and an external resistance equal to the resistance of the longest conductor in the line or track circuit. 55

My invention will be fully described hereinafter, and its novel features carefully defined in the claims.

In the accompanying drawings, which serve to illustrate my invention, I have shown a 60 mechanical device for breaking and closing the shunt-circuit on the locomotive, constructed like or similar to that described and claimed in my said pending application, Serial No. 300,475; but this feature is merely 65 shown for purposes of illustration in connection with my distributer. Any means whatever may be employed for effecting the object accomplished by this mechanical device.

In the said drawings, Figure 1 is a side elevation of a locomotive provided with my improvements, and Fig. 2 is a view showing every part of the device with all the circuits. This view being simply for explanation, the proper proportions of the parts and their relative positions in practice have not been maintained. Figs. 3 and 4 are views, on a small scale, showing the arrangement of the relays and line-wires at two adjacent block-stations along the line of railway. 70 75 80

Referring to the drawings, xx' are the two track-rails of a line of railway, and X is a locomotive thereon.

X' is the cab of the locomotive, and X^2 the pilot thereof. 85

G is the electric-current generator, which I usually mount on the pilot of the locomotive in a suitable box or casing, and B is the distributer as a whole, which is usually mounted in the same box with the generator. 90

Sg is the danger-signal, usually mounted in the cab of the locomotive. This signal may be an ordinary electric bell in a normally-open circuit.

R represents as a whole one of the relays 95 or circuit-breaking devices along the line. Mechanically this device consists of a "safety" electro-magnet S, a "danger" electro-magnet D, an armature-lever l, carrying the armature for both magnets, and a contact piece or screw m. These parts are essentials, but they may be arranged in various ways. 100

The distributor B, Fig. 2, consists mechanically of a suitable base on which is mounted a metal post *g*, in the top of which is mounted a metal rocking lever *h*, bearing two armatures *i* and *i'*, which are adapted to be brought alternately by the rocking of said lever into electrical contact, respectively, with the cores of two electro-magnets *C* and *C'*, mounted on the same base with the post *g*. There is a carbon or other resistance *n* in circuit with the coils of the magnet *C'*. These parts may of course be arranged in any satisfactory way.

In order to make the functions and operation of the distributor fully understood, I will explain the construction of the mechanical circuit-controlling device herein illustrated, premising that the purpose of this device is to break the normally-closed shunt-circuit on the locomotive at the point where the engineer is to receive a danger-signal, if there be any danger, and at the point where the locomotive sets the relays to "danger" and "safety," respectively, and to connect the partial circuit on the locomotive with the partial circuit on the line. Between the track-rails is placed an insulated inclined contact-rail *A*. This rail is placed at the receiving-point where the engineer is to receive the signal of danger. Under the locomotive is mounted a slide *d*, having in its lower end a wheel *a* to contact with and roll on the inclined rail *A*. When wheel *a* is not in contact with rail *A*, an insulated brush *e* forms a metallic contact with the slide *b*; but when the slide *b* is raised by contact of wheel *a* with rail *A* a plate *f*, of insulating material, on the slide is brought under brush *e*. Normally the brush *e* is in electrical contact with the slide *b*.

I will now explain the circuits with reference to Fig. 2. *P* and *N* represent the binding-posts at the positive and negative poles, respectively, of the generator. The current flows from binding-post *P* through the wire *l* to the post *g* of the distributor *B*, thence through the right-hand end of the vibrating or rocking lever *h*, through the armature *i* on said lever, through the core of the electro-magnet *C*, through wire *2*, through the coil of the magnet *C* and the wire *3* to a binding-post *j*, and thence it flows through the wire *4* to the brush *e*, thence to the slide *b*, and thence through the wire *5* to the binding-post *N* at the negative pole of the generator. The circuit described is normally closed and is wholly confined to the locomotive. The wire *4* and brush *e* form the shunt. Now, when the locomotive enters a block the wheel *a* rolls up the incline on the rail *A*, the slide *b* is moved upward, and this breaks the shunt-circuit I have just described by reason of the plate *f* of insulating material being brought under the brush *e*. Instead of flowing through the wire *4* from the binding-post *j*, the current flows from said binding-post through a wire *6* to a wheel *k* of the locomotive, thence to the track-

rail *x*, and thence by a wire *7* to the armature-lever *l* of the relay *R*, thence to the contact-screw *m* of the relay, thence by a wire *8* to the contact-rail *A*, and thence through the wheel *a*, the slide *b*, and the wire *5* back to the generator. Thus it will be seen that if the armature-lever *l* of the relay is in contact with the screw *m*, as seen in Fig. 2, the circuit will remain closed. In this case the engineer will receive no signal. I denominate the magnet *S* of the relay *R* the "safety-magnet," as it serves to set the relay to "safety" by closing the circuit. On the other hand, the magnet *D* of the relay breaks the circuit and sets the relay to "danger," and I therefore denominate it the "danger-magnet."

By reference to Fig. 2 it will be seen that the current flowing from the binding-post *P* to the post *g* of the distributor *B* is divided and a portion of the current flows through a wire *9*, thence through the coil of the magnet *C'*, thence through a wire *10* to the external resistance *n*, which is equal to the external resistance of the longest conductor on the line, and thence through a wire *11* back to the generator. The circuit through the coil of magnet *C'* is always closed, and consequently the magnet is always excited; but owing to the external resistance *n* the magnet *C'* is less powerful than the magnet *C*, which is also in a state of excitation normally.

If the relay for any reason is set to "danger," the locomotive reaches the receiving-point and the contact between its lever *l* and screw *m* is broken, when the wheel *a* rolls up on rail *A* and breaks the locomotive-circuit by moving the plate *f* up under the brush *e*. The current cannot flow through wires *7* and *8* because of the break at the relay. Consequently the magnet *C* is demagnetized, and the magnet *C'*, which is always excited, will attract its armature *i'* into contact with its core, thus closing the normally-open circuit containing the signal or bell *Sg*. The current flows now from the binding-post *P* through wire *l*, post *g*, rocking lever *h*, armature *i'*, the core of the magnet *C'*, and the wire *12* to the bell *Sg* in the cab, and thence back through the wire *13* to the generator. The engineer will thus receive a signal of danger by the ringing of the bell.

In order to stop the bell from ringing and to again close the main circuit through the core of magnet *C*, a "switch" or circuit-closer is employed convenient to the engineer, whereby he can, by simply closing a restoring-circuit, send a current through the coil of magnet *C*. The effect of this is to rock the lever *h* of the distributor, and thus break the bell-circuit and restore the main circuit by the contact of the armature *i* with the core of the magnet *C*. *Sw* is this switch, mounted in the cab of the locomotive. It may as well be an ordinary push-button of the kind known to all electricians; or, indeed, any spring-contact device that will automatically break the

restoring-circuit when the engineer removes the pressure may be employed equally well. I have shown an ordinary lever-switch merely for convenience of illustration. If such a switch were used, the engineer might inadvertently leave the restoring-circuit unbroken. When the engineer closes this switch, the current flows from binding-post P through a wire 14 to the switch or button *Sw*, thence by a wire 15 to and through the coil of magnet C, thence by the wires 3 and 4 to the brush *e*, and thence through the wire 5 to the binding-post N. It will be observed that by the time the engineer shall have had an opportunity 15 to manipulate the switch *Sw* the wheel *a* on the locomotive will have again descended after having passed over the inclined rail A, whereby the brush *e* will have been again brought into electrical contact with slide *b*. The locomotive, having passed the receiving-point and having received no danger-signal, advances into the block to the relay-actuating point or transmitting-point, which will usually be a short distance in advance of the receiving-point.

In Figs. 3 and 4 I have shown a block C and parts of two blocks B and D and stations O and OO, the former at the entrance to block C and the latter at the entrance to block D. 30 The locomotive in Fig. 3 is shown as at the receiving-point at station O and as just entering block C, and the locomotive in Fig. 4 is shown as having entered block C and reached the transmitting-point.

35 Figs. 2, 3, and 4 may be examined together in order to understand the mode of transmitting back to the preceding station.

On the line of railway at the transmitting-point is placed a second contact-rail A', which 40 is exactly like rail A. I have given it a different reference-letter for distinction only. In Fig. 2 this rail is diagrammatically represented as situated just below rail A. When the locomotive reaches this transmitting-point, 45 the wheel *a* rolls up on rail A', and thus simultaneously breaks the locomotive shunt-circuit (through the brush *e*) and shunts into the circuit with the generator G the coil of the danger-magnet D of the relay at station 50 O and the safety-magnet S of the relay at the next station behind—that is, at the entrance to the block B. The current flows (see Fig. 2) from the binding-post P through *l g h i 2 C 3 6 k* to the rail *x*, thence by a wire 15 to the 55 danger-magnet D at station O through the coil of this magnet, thence (see Figs. 3 and 4) back to the preceding station (represented diagrammatically by dotted lines in Fig. 2) through the coil of that magnet, and thence 60 forward by a wire or other conductor 17 to the contact-rail A', thence through the wheel *a*, slide *b*, and wire 5 to the other pole of the generator. The effect of this will be to excite the electro-magnets thus put in circuit 65 and to set the relay at station O to "danger" and the relay at the preceding station to "safety." When the locomotive reaches the

station OO ahead, it sets the relay at this station to "danger" and the relay at station O to "safety." When the locomotive reaches 70 the transmitting-point, (at rail A'), the external resistance in the circuit with the coil of the magnet C of the distributor B will be very considerable. Consequently the attractive power of this magnet, tending to preserve 75 the contact between its core and armature, will be correspondingly weakened; hence, as the magnet C' is always excited, I put an external resistance *n* in circuit with the coil of the magnet C' equal to the greatest resistance 80 that there may be in the transmitting-circuit. Otherwise the magnet C' would overcome 85 magnet C when the transmitting-point was reached, and thus break the main circuit and close the bell or signal circuit. By the use 90 of the distributor B, I avoid all difficulties arising from irregularities due to the varying resistance in the circuits.

In the distributor B, I have shown the cores and armatures of the magnets C and C' as 95 forming contacts and elements of the respective circuits in a manner well understood by electricians; but this is only for convenience, and it is within the ordinary skill of an electrician to substitute other contacts for 100 these.

Having thus described my invention, I claim—

1. A locomotive provided with a distributor, as B, a normally-closed electric circuit 100 including a generator and the coil, armature, and core of one magnet, as C, of said distributor, an electric signal or bell, a normally-open circuit including the generator, the signal-magnet, and the core and armature of 105 the other magnet, as C', of said distributor, and a constantly-closed exciting-circuit including the generator, the coil of the magnet C', and an external resistance, as *n*, substantially as described. 110

2. The combination, with a railway-track provided with a contact-rail at the transmitting-point, two relays at different points along the line, a partial line-circuit including the coils of the danger-magnet D of 115 one relay and the safety-magnet S of the other relay, said partial circuit having for its respective terminals one of the track-rails and the said contact-rail, of a locomotive provided with a distributor B, a partial electric circuit including the generator and the core, armature, and coil of magnet C of said distributor, a normally-open circuit including the generator, the core, and armature of the magnet C' of the distributor, and the 120 electric bell or signal, and a constantly-closed exciting-circuit including the generator, the coil of magnet C' of the distributor, and an external resistance equal to the resistance of the longest conductor on the line. 125 130

3. The combination, with the distributor comprising the electro-magnets C and C', the vibrating armature-lever and armatures, and the resistance *n*, of a circuit including the

generator, the coil of magnet C and its armature and core, the signal-circuit including the generator, the signal, and the armature and core of magnet C', the constantly-closed 5 exciting-circuit including the generator, the coil of magnet C', and the resistance n, and the restoring-circuit including the generator, the coil of magnet C, and the switch or circuit-closer S_w , all arranged to operate substantially as set forth.

4. A locomotive provided with an electric bell or alarm, a normally-open bell-circuit including the generator, an electro-magnet C', which closes the bell-circuit, a constantly- 10 closed electric circuit including the generator, the coil of said magnet, and an external

resistance n, a normally-closed electric circuit including the generator and an electro-magnet C, the coil of which is included in said normally-closed circuit, said magnet C 20 when excited holding the bell-circuit open and its own circuit closed, whereby, when said normally-closed circuit is broken, the bell-circuit will be instantly closed and the alarm sounded.

In witness whereof I have hereunto signed my name in the presence of two subscribing witnesses.

JAMES H. HUNTER.
